STATIC ELIMINATOR.

Application filed March 19, 1923. Serial No. 626,014.

The invention relate to static eliminators for gasoline tanks wherein a filling closure is locked against removal until a lock is released by the insertion of a grounding key or 5 terminal at the end of a grounding cable at a filling station or other point. The object of the present invention is to avoid the possibility of danger that might exist if a spark were to pass as the key approached an open 10 key-hole in the act of inserting the key.

The invention is illustrated in connection with the form of static eliminator disclosed in the application of Charles C. Anthony, Serial No. 590,279, filed September 25, 1922.

15 In the accompanying drawings, forming a part hereof:

Fig. 1 is a plan view of a manhole cover and a filling closure, with the invention applied thereto;

20 Fig. 2 is a sectional elevation of Fig. 1, showing a portion also of the tank shell;

Fig. 3 is an enlarged fragmentary sectional elevation, showing the grounding key partly inserted and about to release the lock; and

25 Fig. 4 is a longitudinal section through the improved key-hole closure, taken in the plane of the grounding key, which is seen inserted and bearing against the lock element.

The gasoline tank is represented in the 30 drawings by a portion of the shell 1, a manhole ring 2, and a manhole cover 3, in which the filling closure 4 is preferably placed, though this may be otherwise. The form of filling closure illustrated is a screw plug 35 adapted to be screwed into and out of a screw-threaded opening in the manhole cover. As in the Anthony application, the filling plug is shown normally locked or obstructed against unscrewing by a two-armed lock-lever 40 over 5 fulcrumed on a bracket 6 on the under side of the manhole cover and urged by a spring 7 so that its inner, upturned arm stands in the path of a lug 8 projecting downward from the filling plug. A hole 9 is 45 formed through the manhole cover for the insertion of a rod or grounding key 10 constituting the terminal of a grounding cable, the key having a suitable insulated handle 11. The key-hole is over the tail or outer 50 arm of the lever 5, so that by pushing the key in the lock is released, the general purpose being to compel grounding of the tank before the filling opening is opened.

The present invention aims to carry the 55 protection further by keeping the smaller

key-hole also closed until grounding has been effected. In the very simple construction adopted for this purpose the key-hole is in fact kept closed at all times, and this is advantageous though not absolutely necessary, as other arrangements may be devised. According to the improvement, therefore, there is a key-hole closure, and the grounding key must be brought into grounding relation to the tank in order that this closure may be 60 opened or brought into position permitting the insertion of the key into the tank.

In the particular preferred construction a plunger housing 12 is secured by screws 13 or otherwise to the top of the manhole cover, over the key-hole, the housing having an extension 9^a of the key-hole in its inner wall. In the housing is a longitudinally movable plunger 14, pressed at one end by a spring 15, which is retained by a disk and a cotter-pin 16. The plunger has an opening 17 corresponding to the key-hole and adapted to register therewith, but normally kept out of register by the spring, which causes the solid part of the plunger to blank the key-hole. 75

In the outer wall of the housing there is a T slot, comprising longitudinal and transverse portions 18, 19, the longitudinal portion permitting the plunger to be moved endwise by pushing the key into the opening 17 and then pressing the key sideways against the resistance of the spring 15. In this way the tank is initially grounded, and when the opening 17 is brought into register with the key-hole, the key can be pushed all the way in to release 80 the lock.

The transverse portion 19 of the T slot enables the key to be engaged with the plunger opening irrespective of turning movement of the plunger in the housing. This 85 permits the use of a simple cylindrical plunger without means to keep it from turning. The plunger is of such length as to prevent binding and to keep the slot closed against entrance of dirt to the interior of the housing when pressed all the way back to the open position.

It will be understood that I do not limit myself to the precise embodiment of the invention, as the form of the device and of the lock with which it cooperates may be varied.

What I claim as new is:

1. In means for electrically grounding a tank by the application thereto of a grounding key forming the terminal of a grounding 110

conductor, a tank having a filling aperture and closure, and a lock for said closure, there being a hole into the interior of the tank for the insertion of said electrical grounding key to release the lock, a closure for said hole and means whereby the key is brought into grounding relation to the tank in order that the said hole closure may be moved into position permitting the insertion 10 of the key.

2. In a static eliminator, a tank having a closure, and a lock for said closure, there being a hole into the interior of the tank for the insertion of an electrical grounding key 15 to release the lock, a slidable spring-pressed closure for said hole having an opening normally out of register with the hole and enabling the said closure to be moved against the spring by means of the key, thereby at 20 once grounding the tank.

3. In a static eliminator, a tank having a closure, and a lock for said closure, there being a hole into the interior of the tank for the insertion of an electrical grounding key to 25 release the lock, a plunger housing outside said key-hole, and a spring-pressed plunger

in the housing movable across the hole and having an opening to receive the key and be moved into register with the hole.

4. In a static eliminator, a tank having a closure, and a lock for said closure, there being a hole into the interior of the tank for the insertion of an electrical grounding key to release the lock, a plunger housing outside 30 said hole, and a spring-pressed plunger in the housing movable across the hole and having an opening to receive the key and be moved into register with the hole, the plunger being free to turn in the housing, and the latter 35 having a T slot, substantially as set forth.

5. In an apparatus for grounding a tank by means of an electrical grounding key, the combination with a tank having a hole for such grounding key, and a lock for a filling closure adapted to be released by the insertion of the grounding key, of a spring-closed 40 closure for said hole forming a grounding element constructed to be moved by the key to position permitting the insertion of the key through the hole.

ARTHUR L. BETTS.
